CLAIM

The ornamental design for a helmet for cyclist, as shown and described.

DESCRIPTION

FIG. 1 is a left, front and top perspective view of a helmet for cyclist showing my new design;
FIG. 2 is a left side elevation view thereof;
FIG. 3 is a right side elevation view thereof;
FIG. 4 is a front elevation view thereof;
FIG. 5 is a rear elevation view thereof;
FIG. 6 is a top plan view thereof;
FIG. 7 is a bottom plan view thereof; and,
FIG. 8 is a perspective view thereof with the fastening belt shown attached.
The fastening belt has been removed in FIGS. 1-7 for clarity of illustration.
